(57) **CLAIM**

The ornamental design for a cassette support base for electrophoresis gel casting, as shown and described.

DESCRIPTION

This application is related to U.S. Design patent application Ser. No. 29/545,637, entitled "Rig for Electrophoresis Gel Casting," and filed on a date even herewith, the entire contents of each of which are incorporated by reference herein.

FIG. 1 is a front perspective view of a first embodiment of a cassette support base for electrophoresis gel casting showing our new design.

FIG. 2 is back perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof.

FIG. 9 is a front perspective view thereof showing environmental structure.

FIG. 10 is a front perspective view of a third embodiment of a cassette support base for electrophoresis gel casting showing our new design.

FIG. 11 is a back perspective view thereof.

FIG. 12 is a front view thereof.

FIG. 13 is a back view thereof.

FIG. 14 is a right side view thereof

FIG. 15 is a left side view thereof.

FIG. 16 is a top view thereof.

FIG. 17 is a bottom view thereof; and,

FIG. 18 is a front perspective view thereof showing environmental structure.

The broken lines depicting a cassette in FIGS. 9 and 18 represent environmental subject matter, and all other broken lines represent portions of the cassette support base that form no part of the claimed design. The broken lines form no part of the claimed design.
